BIGUANIDE SALTS OF PENICILLIN

Joseph F. Weidenheimer, Pearl River, and Lawrence Ritter, Valley Cottage, N. Y., assignors to American Cyanamid Company, New York, N. Y., a corporation of Maine

No Drawing. Application November 13, 1952,
Serial No. 320,334

9 Claims. (Cl. 260—239.1)

1

This invention relates to a new therapeutic composition which has as an essential ingredient a comparatively insoluble organic penicillin salt. More particularly the invention relates to organic salts of penicillin which are less soluble than procaine penicillin and which are non-toxic when injected whereby these compounds may be used for penicillin therapy, giving a blood level which is therapeutically effective over a prolonged period.

This application is a continuation-in-part of our application Serial No. 87,826 filed April 15, 1949, entitled Penicillin Derivatives, and of our application, Serial No. 268,933, filed January 29, 1952, entitled Penicillin Salts, now both abandoned in favor of this application.

It is found that the compounds of this invention may readily be used for the injection of patients with such a quantity that a therapeutically useful concentration of penicillin is maintained in the blood of a normal patient for a period in excess of 48 hours so that additional injections are not required.

The therapeutic composition of this invention has as an essential element thereof a salt of penicillin with a biguanide or substituted biguanide which forms with the penicillin a non-toxic salt of such solubility characteristics that the material when administered to a subject is therapeutically available at such a rate as to build up sufficient penicillin concentration to be effective against the particular organism for which the treatment is being given but yet which is not sufficiently soluble to permit all of the penicillin to be dissipated within a comparatively short period.

The biguanide salts of penicillin of this application may also be used in processes of refining penicillin as they form salts by which penicillin may be precipitated from solutions containing the penicillin. Also, certain of these salts are extremely insoluble and stable under adverse conditions so that the salts may be used as additives for foodstuffs where the penicillin salt is distributed and where conventional salts of penicillin would be inactivated due to moisture present.

Among the biguanides, the para-halophenyl-biguanides, the 5-nitrogen of which may be substituted by one or more alkyl groups, have been found to be particularly efficacious. The preparation and certain characteristics of some of these biguanides are disclosed and set forth in a U. S. patent to Daniel E. Nagy, No. 2,455,896 entitled "1-Aryl, 5-Alkyl Biguanides"; a British

5 Patent 577,843 to Francis H. S. Curd and Francis L. Rose, entitled "Biguanide Derivatives"; a U. S. patent to Francis H. S. Curd and Francis L. Rose, 2,467,371, entitled "Biguanide Derivatives" and a U. S. patent to Daniel E. Nagy, 2,455,897, entitled "1,5-Diarylbiguanides from Aromatic Amines and Dicyanamide."

Certain of the biguanide penicillins are sufficiently heat stable that the salts may be sterilized by the use of heat, as for example, 110° C. for 10 hours, thereby enabling the sterilization of the penicillin salts at a later and more convenient stage in their manufacture.

10 Any of the penicillins may be used in this invention. At present the medical profession prefers penicillin G, and accordingly the penicillin G salts are those which are normally prepared. From the standpoint of convenience and preparation, the availability of intermediates and the 15 comparatively low cost of the material, the 1-(p-chlorophenyl)-5-isopropyl biguanide compound of penicillin G is among those which are normally commercially preferable.

20 The chemistry appears to be that of the straight reaction between an acid and a base. Penicillin forms alkaline salts very readily and the herein used biguanides from acid salts.

25 As a method of preparation it is normally most convenient to mix an alkali, or alkaline earth metal, or a suitable organic base, salt of the desired variety of penicillin with a calculated quantity or slight excess of an acid salt of the desired biguanide thereby forming the desired complex. From the standpoint of cost and availability the 30 salts most commonly used are the sodium, potassium, calcium or triethylamine salts of penicillin and a halide, usually hydrochloride, salt of the biguanide such as 1-(p-chlorophenyl)-5-isopropyl biguanide hydrochloride. There is thereby 35 formed the desired salt, and sodium, calcium, potassium or triethylamine halide, such as chloride, which material is readily removed from the desired biguanide penicillin, although no harm is done if such a salt is injected with the penicillin. It may be that some type of complex other 40 than that classed as a true salt is formed by the interaction of the specific biguanides and penicillins herein mentioned, but for purposes of convenience the reaction product will be referred to as a salt because it exhibits certain of the properties of salts and probably is properly classed as a salt.

45 In the preparation of these salts the initial crystallization at times requires considerable stirring and cooling, but normally the crystal

habit is such that the crystals as formed are suitable for injection. In some instances recrystallization from suitable solvents may be desired.

For purposes of injection it is desired that the particular biguanide penicillin salt be suspended in a suitable medium such as distilled water, normal saline, 20% propylene glycol or other commonly used aqueous diluent or in an oil such as peanut oil, sesame oil, cottonseed oil or other assimilable triglyceride, together with such stabilizing agents, buffers, thixotropic agents, viscosity modifiers and wetting agents as may be desired to cause the material to have a fluidity and stability such that it may be easily filled into a hypodermic syringe and injected into a patient.

Additionally, it is frequently desirable to have mixed with this soluble penicillin salt a water soluble penicillin type such as the sodium or potassium or calcium salt which will cause a high initial blood level of penicillin in a patient so that by the combination the patient receives a very rapid, high blood level caused by the soluble penicillin derivative and there is maintained in the patient a therapeutic level of penicillin over a prolonged period because of the low solubility and lowered rates of absorption of our specific biguanide derivatives of the penicillin.

Certain of the biguanide derivatives of penicillin, particularly 1-(p-chlorophenyl)-5-isopropyl biguanide penicillin, may be used in lieu of procaine penicillin in the various forms of ointments and suspending media now used for procaine penicillin and thereby will be obtained a product possessing superior stability and a greater period of therapeutic efficacy.

In certain instances the 1-(p-chlorophenyl)-5-isopropyl biguanide will be found to have a therapeutic effect of its own although normally patients requiring penicillin do not require treatment with 1-(p-chlorophenyl)-5-isopropyl biguanide. The concentration of 1-(p-chlorophenyl)-5-isopropyl biguanide which is built up in the patient is not sufficiently high to cause any complications and is less than that which is frequently used as a prophylactic in malaria control.

In some instances for patients who are particularly sensitive there may be added to the mixture a local anesthetic to prevent pain at the point of injection.

Because of the greater insolubility in water, if 1-(p-chlorophenyl)-5-isopropyl biguanide is added to a procaine penicillin solution there will be formed a 1-(p-chlorophenyl)-5-isopropyl biguanide penicillin and free procaine which may be as the hydrochloride. It may be convenient to have procaine or other anesthetic present either from this or other sources so that the sensitivity at the point of injection is diminished.

Whereas our compounds may be formed by the interaction of salts of penicillin and salts of the specific biguanides, which are to be used, they may also be formed by the reaction of free penicillin and the free biguanide. They may be formed in a water solution, or in an aqueous medium such as a mixture of water and alcohol, in an alcohol medium containing a large proportion of alcohol, in water, or even an anhydrous alcohol, or any of the various organic solvents in which the particular biguanides and penicillins are each somewhat soluble and the solubility characteristics of all of the compounds are such that the desired products are formed thereby, even, for example, by removal of the solvent

or other methods well known to those desiring to manufacture salts.

More particularly, our invention includes the salts of penicillin such as penicillin G F. X and other penicillins, hereinafter called penicillin, with a basic compound from the group consisting of biguanide and compounds containing a biguanide nucleus of the formula

where R_1 , R_2 , R_3 and R_4 may be either hydrogen or such radicals as alkyl, alkenyl, alkynyl, cycloalkyl, monocyclic aryl, polycyclic aryl, monocyclic aroyl, 5 membered monocyclic heterocyclic radicals and 6 membered monocyclic heterocyclic radicals, which radicals may either be the simple radicals or substituted. It is found that such radicals as are mentioned above may have on the aliphatic portions such substituents as hydroxy, alkoxy, aryl and nitrile groups and on the aromatic portions such groups as alkyl, aryl, halogen, nitro, alkoxy, aryloxy, nitrile, hydroxy and carbethoxy groups. We prefer that not more than two of these substituent groups be aromatic radicals as otherwise the basicity of the biguanide is less than is preferred for the formation of the biguanide salts. For penicillin salt formation R_5 and R_6 may be either hydrogen or lower alkyl groups, but it is normally more convenient to prepare the biguanides where R_5 and R_6 represent hydrogens. Where R_2 is hydrogen, R_1 and R_5 are equivalent, as the hydrogen is labile. Similarly, where R_4 is hydrogen, R_3 and R_6 are equivalent.

To list all biguanides with which our salts may be formed would unduly lengthen this disclosure, but by way of example, certain typical ones are listed. Among the new salts of our invention are the salt of penicillin with:

- 1-ethylbiguanide
- 1,1-diethylbiguanide
- 1,2-diethylbiguanide
- 1,5-diethylbiguanide
- 1-ethyl-5-propylbiguanide
- 1,1-diethyl-2-ethylbiguanide
- 1,1-diethyl-5-ethylbiguanide
- 1,1,2-triethyl-5-propylbiguanide
- 1-beta-hydroxyethylbiguanide
- 1-beta-methoxyethylbiguanide
- 1,1-dibutylbiguanide
- 1-beta-cyanoethylbiguanide
- 1-beta-(orthochlorophenyl)-ethylbiguanide
- 1-beta-phenylethylbiguanide
- phenylbiguanide
- o-tolylbiguanide
- 1-octadecyl-5-phenylbiguanide
- 1-butyl-5-octylbiguanide
- 1-benzenesulfonyl-5-phenylbiguanide
- 1-butyl-5-phenylbiguanide
- 1,4-diphenyl-3,5-diisopropylbiguanide
- 1,5-diphenylbiguanide
- 1,5-di-p-chlorophenylbiguanide
- 1-dodecyl-5-phenylbiguanide
- 1-dodecyl-5-p-sulfonamidobiguanide
- 1,1-dibutyl-5-phenylbiguanide
- 1,5-dimethyl-1,5-diphenylbiguanide
- 1,5-di-beta-naphthylbiguanide
- 1,5-di-o-chlorophenylbiguanide
- 1,5-di-m-chlorophenylbiguanide
- 1,5-di-p-methoxyphenylbiguanide
- 1,5-di-p-bromophenylbiguanide
- 1,5-di-p-nitrophenylbiguanide

- 1-(o-biphenyl) biguanide
 1-m-methoxyphenylbiguanide
 1-m-phenoxyphenylbiguanide
 1-m-cyanophenylbiguanide
 1-p-hydroxyphenylbiguanide
 1-p-carbethoxyphenylbiguanide
 1,1-dibutyl-5-methyl-5-phenylbiguanide
 1-butyl-5-methyl-5-m-tolylbiguanide
 1,1-di-beta-hydroxyethyl-5-p-tolylbiguanide
 1-allyl-5-alpha-naphthylbiguanide
 1-n-hexyl-5-ethyl-5-p-tert-amylphenylbiguanide
 1-tert-amyl-5-o-anisylbiguanide
 1,1-pentamethylene-5-p-nitrophenylbiguanide
 1-cyclohexyl-5-ethyl-5-p-chlorophenylbiguanide
 1,1-diallyl-5-p-cyanophenylbiguanide
 1,5,5-tributylbiguanide

Any of the above listed penicillin salts may be formed by reaction of penicillin and the biguanide. As illustrative, examples showing the production of such salts in accordance with this invention are:

EXAMPLE 1

In a mixture of 2500 milliliters of distilled water and 750 milliliters of ethyl alcohol were dissolved 125 grams of 1-(p-chlorophenyl)-5 isopropyl biguanide acetate. In an equal volume of a similar solution were dissolved 175 grams of the triethylamine salt of penicillin. The 1-(p-chlorophenyl)-5 isopropyl biguanide acetate solution was filtered through a sterilizing filter into a previously sterilized reaction vessel equipped with mechanical stirrer, inlet tubes and a filter foot. The triethylamine penicillin was sterile filtered and slowly introduced into the reaction vessel with stirring. After about $\frac{1}{5}$ of the penicillin solution had been introduced, the reaction mixture was steriley seeded to induce crystallization. The remainder of the penicillin solution was added over a period of about 1 $\frac{1}{2}$ hours, the 1-(p-chlorophenyl)-5 isopropyl biguanide penicillin crystallizing as formed. The mixture was placed in the chill room at approximately 0° C. for two hours to insure complete precipitation. The solvent was removed through the filter foot and the residual 1-(p-chlorophenyl)-5 isopropyl biguanide penicillin crystals washed with approximately 1 liter of sterile distilled water and dried for 48 hours. The entire procedure, after the sterile filtrations, was carried out under sterile conditions, so that the material as formed was sterile. There was obtained a yield of 163 grams, or 69% of the theoretical yield. Theoretically the material should assay 1015 units per milligram; on actual bioanalysis it was found to show 1043 units per milligram. The 1-(p-chlorophenyl)-5 isopropyl biguanide penicillin as thus formed was found to have a melting point of approximately 161-162° C. and was found to be soluble to the extent of approximately 0.25% in water. 200 milligrams of the thus obtained 1-(p-chlorophenyl)-5 isopropyl biguanide penicillin dry was mixed with sufficient sesame oil to form 1 cc. of a suspension, thereby forming an injectable therapeutic dose which is satisfactory for injection into a patient to maintain a therapeutic penicillin level for a prolonged period.

EXAMPLE 2

To a solution of 125 grams of 1-(p-chlorophenyl)-5 isopropyl biguanide acetate in 2500 milliliters of distilled water and 750 milliliters of alcohol was added slowly with stirring a solu-

tion of 137 grams of sodium penicillin in 1000 milliliters of distilled water. After approximately 20% of the penicillin had been run in, the addition was stopped and the material seeded with 1-(p-chlorophenyl)-5 isopropyl biguanide penicillin crystals. As the solution became opalescent indicating that crystallization had commenced, the remainder of the penicillin was added over a period of approximately 1 $\frac{1}{2}$ hours with continuous stirring. Strict conditions of cleanliness were maintained but the materials were not sterile nor sterilized. The suspension was placed in a chill room at approximately 0° C. overnight to allow complete precipitation, and the solvent removed. The residual crystals of 1-(p-chlorophenyl)-5 isopropyl biguanide penicillin were washed with distilled water and dried at room temperature in a desiccator for 48 hours giving a yield of 195 grams or 87% of the theoretical amount. The 1-(p-chlorophenyl)-5 isopropyl biguanide penicillin was filled into ampoules containing the desired dosages and the ampoules were sterilized in an oven at 110° C. for 8 hours. Thereby were obtained sterile ampoules containing dry 1-(p-chlorophenyl)-5 isopropyl biguanide penicillin in the desired dosage units. For injection, to such an ampoule may be added a sufficient quantity of a sterile aqueous 20% propylene glycol diluent to form a suspension having the desired concentration for injection into the patient.

EXAMPLE 3

116 grams of 1-(p-chlorophenyl)-5 isopropyl biguanide hydrochloride were dissolved in a solution of 2500 milliliters of distilled water and 750 milliliters of alcohol. Thereto was added 150 grams of potassium penicillin G in a solution of 2500 milliliters of distilled water and 750 milliliters of alcohol. The penicillin was added slowly with stirring; the mixture being seeded to insure crystallization, after part of the penicillin-containing solution was added. The mixture was stirred thoroughly and permitted to stand overnight. The crystals were removed from the solvent thereby being obtained 1-(p-chlorophenyl)-5 isopropyl biguanide penicillin in an unsterile condition. The thus prepared 1-(p-chlorophenyl)-5 isopropyl biguanide penicillin was sterilized by heating to 110° C. for 10 hours; after which it was ready for blending, mixing and filling under sterile conditions for therapeutic use.

EXAMPLE 4

125 grams of 1-(p-chlorophenyl)-5 isopropyl biguanide acetate was powdered and suspended in 1 liter of distilled water. Thereto was added a solution of 175 grams of triethylamine penicillin dissolved in 1 liter of water. The suspension was stirred for 5 hours with a small quantity of crystalline 1-(p-chlorophenyl)-5 isopropyl biguanide penicillin added as seed during the first hour. The desired 1-(p-chlorophenyl)-5 isopropyl biguanide penicillin was separated from the aqueous layer, washed with water to remove salt, and dried under high vacuum for 48 hours. The dried material was sterilized by heating to 110° C. for 8 hours. The thus prepared dry sterile 1-(p-chlorophenyl)-5 isopropyl biguanide penicillin was mixed with sterile potassium penicillin and the mixture filled into vials, each vial containing a sufficient quantity of each of the 1-(p-chlorophenyl)-5 isopropyl biguanide penicillin and potassium penicillin to provide, when mixed with a normal saline diluent, a therapeutic

7
dose giving high initial levels and prolonged levels in accordance with the desire of the user.

EXAMPLE 5

5 grams of 1-(p-chlorophenyl)-5 isopropyl biguanide acetate were dissolved in a mixture of 100 milliliters of water and 30 milliliters of ethyl alcohol. Thereto were added 7.15 grams of the triethylamine salt of penicillin G dissolved in 100 milliliters of water and 30 milliliters of alcohol over a period of one hour. A very small quantity of seed crystals were added, the crystallization beginning almost immediately, and at the end of the mixture was quite pasty. The mixture was stirred for an additional hour at 0° C., the crystals collected, washed in distilled water, and dried in vacuo. There was obtained a yield of 86% of the theoretical analyzing 1040 units per milligram and melting at 161-162° C. and showing an analysis of:

	Per cent
Carbon	55.54
Hydrogen	5.94
Nitrogen	17.25
Sulphur	5.80
Chlorine	6.19

EXAMPLE 6

960 grams of para-chlorophenyl-biguanide hydrochloride dissolved in a mixture of 25 liters of water and 5 liters of ethyl alcohol were treated with 2.2 kilograms of the triethylamine salt of penicillin dissolved in 25 liters of water and 5 liters of alcohol. The penicillin solution was added to the biguanide solution and when an opalescent solution was obtained, the mixture was seeded and stirred until crystallization began, the remainder of the penicillin solution then being slowly added. The crystals formed, clusters of thin rods, were collected, washed with water and dried in vacuo. There was obtained a yield of 63% of the theoretical; the crystals melted at 121-122° C. (uncorrected), the material was soluble to the extent of 0.3% in water. Because the crystals melt so close to the temperatures required for heat sterilization, as a matter of convenience the product is prepared under sterile conditions to obviate the necessity of heat sterilization after its preparation. The material was found to have an activity of 1079 units per milligram, and on analysis showed:

	Per cent
Carbon	52.80
Hydrogen	5.14
Nitrogen	17.99

EXAMPLE 7

960 milligrams of para-chlorophenyl-biguanide hydrochloride were suspended in 15 milliliters of water which was treated with a solution of 1.8 grams of sodium penicillin G dissolved in 15 milliliters of water. As the penicillin solution was added the mixture was stirred vigorously and seed crystals were introduced. The suspension was stirred for 3 hours, the penicillin salt collected, washed with water, and dried in vacuo. The material appeared to be identical with that of the preceding example.

EXAMPLE 8

1 gram of 1,1-dibutyl-5-(para-iodophenyl)-biguanide hydrochloride was dissolved in 15 milliliters of water and 15 milliliters of alcohol. The clear solution was then treated with a solution of 1 gram of potassium penicillin dissolved in a mixture of 7.5 milliliters of water and 7.5

milliliters of alcohol. An oil was formed which upon storage overnight at 4° C. yielded crystals in hexagonal plates which were collected, dried and found to assay 751 units per milligram.

8

5

EXAMPLE 9

Phenylbiguanide penicillin

10 1 gram of phenylbiguanide hydrochloride dissolved in 20 milliliters of water is added with stirring to a solution of 2 grams of triethylamine penicillin G dissolved in 20 milliliters of water. An oil is deposited which does not crystallize readily on standing. The supernatant liquid is 15 decanted to yield a gummy residue which upon drying in a vacuum oven yields a dry semicrystalline powder. The power analyzes 917 units per milligram.

20

EXAMPLE 10

o-tolylbiguanide penicillin

1 gram of o-tolylbiguanide hydrochloride dissolved in 20 milliliters of water is added with stirring to a solution of 1.9 grams of triethylamine penicillin G in 20 milliliters of water. A gum is deposited which upon drying in a vacuum oven yields a dry powder having a potency of 930 units per milligram.

30

EXAMPLE 11

1-octadecyl-5-phenylbiguanide penicillin

35 A solution is prepared of 0.5 gram of 1-octadecyl-5-phenylbiguanide hydrochloride, as the free base, in 15 milliliters of ether. A solution of 0.4 gram of the free acid form of penicillin (penicillanic acid) in 30 milliliters of ether is added with stirring. The resulting clear ethereal solution is evaporated to dryness, yielding the amorphous 1-octadecyl-5-phenylbiguanide penicillin.

40

EXAMPLE 12

1,5-diphenylbiguanide penicillin

45 4.1 grams of 1,5-diphenylbiguanide hydrochloride dissolved in a mixture of 50 milliliters of ethyl alcohol and 25 milliliters of water. This solution is added to a solution of 5 grams of sodium penicillin in 25 milliliters of water. The combined mixtures are stirred and on cooling, the desired 1,5-diphenylbiguanide penicillin salt separates as crystals.

55

EXAMPLE 13

1,5-di-p-chlorophenylbiguanide penicillin

55 5 grams of 1,5-di-p-chlorophenylbiguanide hydrochloride is suspended in 25 milliliters of ethyl alcohol and 50 milliliters of water. To this is 60 added dropwise with stirring a solution containing 5 grams of crystalline sodium penicillin G in the same solvent. The biguanide hydrochloride dissolves and the desired 1,5-di-p-chlorophenylbiguanide penicillin precipitates in crystalline form. The precipitate is collected, washed with water, and dried. The yield is 8.7 grams of material assaying 861 units per milligram. The melting point is approximately 161° C. and the material is soluble to the extent of 0.0145% in water. The low solubility makes this salt particularly useful as an additive for poultry feed. A sample of this salt, upon being heated at 110° C. for 11 hours, is found to have a potency of 833 units per milligram, showing that the salt may be heat sterilized.

EXAMPLE 14

1,5-di-alpha-naphthylbiguanide penicillin

5 grams of 1,5-di-alpha-naphthylbiguanide hydrochloride is mixed with 50 milliliters of alcohol and 50 milliliters of water. Thereto is added 5 grams of sodium penicillin in 25 milliliters of water. On cooling and standing, the amorphous 1,5-di-alpha-naphthylbiguanide penicillin separates out.

Other biguanides acid salts such as the sulfate, the nitrate, the phosphate or the acetate may be used instead of the hydrochloride salts. A wide variety of salts of penicillin may be used but the alkali or ammonium or alkylamine salts are particularly convenient. The reaction may be carried out in water, methanol, ethanol, propanol, butanol, 2-ethoxyethanol, 2-methoxyethanol, other alkoxy ethanols, other alcohols, dioxane, formamide, dimethylformamide, acetone, methyl ethyl ketone, or methyl isobutyl ketone, or mixtures of two or more of these solvents or other similar solvents.

Having thus set forth by description and example certain aspects thereof, as our invention we claim:

1. The salt of penicillin and a compound of the formula

where R_1 represents a member selected from the

group consisting of alkyl, monocyclic aryl, halo-monocyclic aryl, and dicyclic aryl radicals; R_2 represents a member selected from the group consisting of hydrogen, alkyl, monocyclic aryl, chloromonocyclic aryl, and dicyclic aryl radicals; and R_3 represents a member selected from the group consisting of hydrogen and alkyl radicals.

5 2. A salt of a penicillin and a compound of the formula

15 where n and m are small whole numbers not less than 0, and X is a halogen.

3. The salt of penicillin and 1-(p-chlorophenyl)-5 isopropyl biguanide.

4. The salt of penicillin G and 1-(p-chlorophenyl) 5 isopropyl biguanide.

20 5. The salt of penicillin and parachlorophenyl biguanide.

6. The salt of penicillin and 1,5-di-p-chlorophenylbiguanide.

7. The salt of penicillin and 1,5-diphenylbiguanide.

25 8. The salt of penicillin and 1,5-diarylbguanide.

9. The salt of penicillin and 1,5-di-alpha-naphthylbiguanide.

30 JOSEPH F. WEIDENHEIMER.
